MEANS FOR DISPENSING LATEX AND
THE LIKE

Austin H. Beaumier, North Hollywood, Calif.

Application March 2, 1942, Serial No. 432,958

3 Claims. (Cl. 15—139)

This invention relates to dispensers and more especially to a dispenser for latex and similar materials.

An object of the invention is to provide a simple, practical and inexpensive article of the character described.

Another object of the invention is to provide an improved and more efficient means of dispensing latex and similar viscous materials having fast drying properties.

An additional object is to provide a guide tube for a dispenser adapted for efficient application of cementitious material to the edge portions of fabric such as carpeting.

Other objects and advantages will appear and be brought out more fully in the following specification, reference being had to the accompanying drawing, wherein:

Fig. 1 is a sectional view of a dispenser and guide tube embodying my invention.

Fig. 2 is a sectional view taken along the line 2—2 of Fig. 1.

Fig. 3 is a sectional view taken along the line 3—3 of Fig. 1.

Fig. 4 is a perspective view showing the air inlet valve and connections, and,

Fig. 5 is a fragmentary view showing the rock lever.

Referring more particularly to the drawing I show a dispenser 10 having a generally cylindrical portion 11 and a threaded neck 12 for connection to the neck of a container 13 or other reservoir of liquid or viscous latex or similar cementitious material. Cylindrical portion 11 has an annular end portion 14 recessed to receive and hold a flared cap 15 provided with a circular dispensing aperture 16.

Dispenser 10 has a cylindrical portion 17 provided with an end plate 18 having an aperture 19 for a conical bleeder valve member 20. Member 20 has a lever arm 21 and plate 18 has an extension 22 adapted to form a fulcrum whereby to lift valve 20 from seat 19 when lever 21 is pressed downwardly as indicated.

A rod or pin 23 is suitably positioned in cylinder 11 and a rock lever 24 is mounted thereon. Lever 24 has an aperture 25 at one end for engaging a link 26 which has a semi-spherical ball seat 27 for a marble ball valve 28 adapted to normally close dispensing aperture 16. An eyelet 29 or the like is secured to valve 28 and provides a flexible connection with a link member 30 to which is suitably secured a saddle 31 having an elongated slot 32 for engagement with the angular end portion 26a of member 26 which extends through aperture 25 of arm 24. A spring 33 is connected to eyelet 29 and an aperture 34 in arm 24.

The operation of the invention as thus far described should be apparent. The latex or other material which fills cylinder 11 is normally re-

tained therein since spring 33 maintains valve 20 and ball valve 28 in closed position. The latex may be dispensed by a pressure on the surface to be applied which pushes ball valve 28 away from aperture 16 and the cementitious material runs out. If however it is desired to admit air into cylinder 11 valve lever 21 can be depressed raising valve 20 from seat 19 and the air thus admitted permits a more rapid flow of the dispensed liquid through dispensing aperture 16. This latter movement of valve lever 21 will by engagement of saddle 31 and extension 26a raise ball guide 27 and the pressure of the liquid will force itself out and raise ball valve 28 from dispensing aperture 16.

I show a dispensing guide tube fixture 35 having a neck portion 36 adapted to fit over cap 15 and the end portion of cylinder 11 and having a slot portion 37 forming a pair of guide abutments 38. By this structure the edge portions 39 of a pair of fabric pieces 40 to be cemented together can be placed in slot 37 and the edge portions 39 will be adjacent dispensing aperture 16. The dispenser can thereupon be passed over edges 39 dispensing the latex or other cementitious material thereon, which edges can thereafter be brought together for the drying of the cementitious material.

Having described my invention what I claim is:

1. A dispenser as described comprising a tubular body having a dispensing aperture, a ball valve for said aperture, a supply inlet for said body, a rock lever pivotally mounted in said body, a ball retaining link connected to said rock arm, a bleeder valve having an actuating lever, a spring connected to said bleeder valve and rock arm, and a link connected to said bleeder valve and rock arm.

2. A dispenser as described comprising a tubular body having a dispensing aperture, a ball valve for said aperture, a supply inlet for said body, a rock lever pivotally mounted in said body, a ball retaining link connected to said rock arm, a bleeder valve having an actuating lever, a spring connected to said bleeder valve and rock arm, and a lost motion link connected to said bleeder valve and rock arm, said ball valve adapted to open by external pressure applied to said ball, said bleeder valve being kept closed by said spring.

3. A guide tube for a dispenser as described having a dispensing neck provided with an aperture, said guide tube adapted to be detachably secured to said neck and having a slot adapted to receive the edge portion of a flat element, said tube having an abutment at the bottom of said slot to engage said element edge portion for positioning said edge portion adjacent said dispensing neck aperture.

AUSTIN H. BEAUMIER.
